UNITED STATES PATENT OFFICE.

EDWIN J. EVANS AND GEORGE E. HEMPHILL, OF SALT LAKE CITY, UTAH, ASSIGNEES
TO UNIVERSAL TOOL COMPANY, A CORPORATION OF UTAH.

MONKEY-WRENCH.

1,391,179.

Specification of Letters Patent. Patented Sept. 20, 1921.

Application filed December 30, 1920. Serial No. 434,082.

To all whom it may concern:

Be it known that we, EDWIN J. EVANS and GEORGE E. HEMPHILL, citizens of the United States, residing at Salt Lake City, 5 in the county of Salt Lake and State of Utah, have invented certain new and useful Improvements in Monkey-Wrenches, of which the following is a specification.

Our invention relates to wrenches, and 10 has for its object to provide a simple monkey wrench which may be adjusted to fit nuts of different sizes by new and novel adjusting means.

These objects we accomplish with the device illustrated in the accompanying drawings in which similar numerals of reference indicate like parts throughout the several views, and as described in the specification forming a part of this application and 20 pointed out in the appended claims.

In the drawings in which we have shown a substantial embodiment of our invention, Figure 1 is a longitudinal section of the wrench in parallel with the planes of the 25 jaws. Fig. 2 is an inverted plan view of the wrench, with the movable jaw and differential rod removed. Figs. 3, 4, 5, 6, and 7 are views in cross-section on lines 3—3, 4—4, 5—5, 6—6, and 7—7 of Fig. 1 respectively. 30 Fig. 8 is a side elevation of the movable jaw and Fig. 9 is an end elevation of the same jaw.

We use the helical screw principal commonly used in certain screw drivers to adjust our movable jaw, and the invention consists in the combination of parts and construction of the helical screw changed to meet the requirements of a monkey wrench, and as shown in the drawings the shank 1 40 has an integral fixed jaw 2. The said shank and jaw are centrally bored, as at 3, to form a bearing for the differential rod, which rod has end bearings as well. The said shank is slotted from end to end, as at 4, which 45 slot opens to the interior bore 3, and has a portion widened, as at 5, to receive the guide flanges of the slideable jaw. The engaging face of the said jaw 2 is bored to form an end bearing for the rod 6, and said jaw is 50 also perforated by a transverse guide slot in line with the guide flanges of the movable jaw. The said shank 1 is internally threaded at its free end to receive a bearing nut 7 for the end of the differential rod 6, and said 55 shank is given an ovoid form in cross sec-

tion to form the handle of the wrench, and on said handle is carried the operating sleeve 8. The said shank is interiorly recessed from the slot 5 to its end, and said recess extends through the jaw 2 to form a guide race 9 within which the guide flanges of the movable jaw are operated. The movable jaw 10 has an integral web portion 11 extending longitudinally toward the said sleeve 8, a portion of which web is widened or flanged, 60 as at 12 and herein designated as guide flanges, and which portion is operated in the recess or guide race 9. The said portion of the jaw is given the length of the slot 5 in order that it will pass through said slot in 65 assembling the parts of the wrench. The face of said portion 12 is transversely threaded, as at 13, to provide raised threads which engage in the helical groove 14 of the differential rod 6. The differential rod 6 has 70 a helical groove 15 cut into its periphery from the bearing portion, which engages in the bearing nut 7, to near the end of said web portion 11 of the shank, with the pitch of the grooves about one inch to each convolution, also a helical groove 14 cut from the 75 end of said groove 15 to the end of said rod, and whose pitch is much greater than the pitch of the groove 15, preferably about five convolutions to the inch. A radially disposed pin 16 is fastened in said sleeve 8 with its inner end engaging in said groove 15, 80 while the threads 13 of the guide flange 12 engage in the groove 14.

We thus provide a monkey wrench having 85 but few parts which are assembled by inserting the portion 12 of the movable jaw through the said slot 5 into the recess 9, with the threads 13 engaging in the groove 14 of the rod 6, and when the two jaws are 90 contiguous the bearing nut 7 is screwed into place in the end of the shank 1. The sleeve 8 is then placed on the handle end of the shank and the pin 16 screwed into place with its inner end engaged in the groove 15, when 95 the wrench is ready for use. The jaw 10 is moved relative to the jaw 2 by slipping the sleeve 8 along the shank 1. The difference in the pitch of the grooves 14 and 15 will allow a five or six inch movement of the 100 sleeve while the jaw 10 will be moved only about one inch, thus providing the adjustment of the jaws by the rotation of the differential rod 6.

Having thus described our invention we 110

desire to secure by Letters Patent and claim—

1. A monkey wrench comprising a longitudinally slotted and centrally bored shank 5 with a jaw integral therewith; a rod having a helical groove cut therein and of two different pitches adapted to operate in the bore of said shank; a movable jaw; a flanged extension thereon having its face trans- 10 versely threaded to engage in one portion of the groove of said rod and with the flanges engaging the edges of the slotted portion of said shank; a sleeve carried on said shank; and a pin fastened in said sleeve with its end 15 engaged in the other portion of said groove.

2. A monkey wrench comprising a longitudinally bored and slotted shank and a fixed jaw integral therewith; and provided

with a guide recess; a spindle rod having spiral grooves cut therein of different pitches 20 with the convolutions running the same direction and carried and operable within the bore of said shank; a movable jaw having a flanged web on one edge which web extends beyond the nut engaging end of said jaw 25 and the whole web flange engaging in the guide recess of said shank and fixed jaw; threads cut in the face of said flanged web portion of said movable jaw; a sleeve carried on said shank; and a pin in said sleeve 30 having one end engaged in one set of grooves of said spindle rod.

In testimony whereof we have affixed our signatures.

EDWIN J. EVANS.

GEORGE E. HEMPHILL.
